US00D552323S

(12) **United States Design Patent** (10) **Patent No.:** **US D552,323 S**
Perrier et al. (45) **Date of Patent:** **** Oct. 2, 2007**

(54) **DISPLAY DEVICE**

(75) Inventors: **R. Sylvain Perrier**, Ottawa (CA); **Jeremy List**, Ottawa (CA); **Cliff Read**, Carp (CA); **Jason Busschaert**, Towson, MD (US); **Mark Edey**, Ottawa (CA); **James D. Miller**, Holland Landing (CA); **Howard W. Overland**, Aurora (CA)

(73) Assignee: **Springboard Retail Networks Licensing SRL** (BB)

(**) Term: **14 Years**

(21) Appl. No.: **29/269,318**

(22) Filed: **Nov. 29, 2006**

Related U.S. Application Data

(62) Division of application No. 29/241,458, filed on Oct. 28, 2005.

(30) **Foreign Application Priority Data**

Apr. 29, 2005 (CA) 110971

(51) **LOC (8) Cl.** **12-02**

(52) **U.S. Cl.** **D34/27**

(58) **Field of Classification Search** D34/12-27; 40/308, 506, 611; 280/33.991, 62, 47.17, 280/646, 33.992; D12/133; 403/312; 235/383

See application file for complete search history.

(57) **CLAIM**

The ornamental design for a display device, as shown and described.

DESCRIPTION

FIG. 1 is a front right perspective view of the display device; FIG. 2 is a rear perspective view of the display device of FIG. 1;

FIG. 3 is a front elevation view of the display device of FIG. 1;

FIG. 4 is a rear elevation view of the display device of FIG. 1;

FIG. 5 is a top plan view of the display device of FIG. 1; FIG. 6 is a bottom plan view of the display device of FIG. 1;

FIG. 7 is a right side view of the display device of FIG. 1; and,

FIG. 8 is a left side view of the display device of FIG. 1.

The broken line showing of the face and back surfaces is included for the purpose of illustrating only and forms no part of the claimed design.

1 Claim, 4 Drawing Sheets
